AUTOMATIC LOCKING KEY SAFE
 Harry H. Mallett, 560 Prospect St., Westfield, N.J.
 Filed Aug. 15, 1961, Ser. No. 131,675
 3 Claims. (Cl. 312—319)

My invention relates to automatic locking key safes and the like and in particular to the type of key safe used by real estate brokers where a single house key is made available to several authorized persons who each have a master key to the safe containing the house key; such safe usually being attached to the house to be entered.

Prior to my invention there was no way to be positively assured, after a house key had been removed from a key safe, that it was returned to the key safe or, if returned, that the key safe was securely locked to prevent unauthorized persons from using the key to enter the house.

One of the objects of my invention is the provision of a key safe which, when unlocked by an authorized person, will only permit the removal of the house key as far as the lock of the house.

Another object of my invention is to provide a key safe so constructed that when an authorized person has used the house key contained therein the key will automatically be returned to the key safe compartment and the compartment will automatically lock itself.

Other objects and advantages of my invention will be apparent from the specifications and drawings in which:

FIG. 1 is an end view of the front of the key safe box.
 FIG. 2 is a side view of the safe shown in FIG. 1.

FIG. 3 is a cross-sectional side elevation of the safe shown in FIG. 2.

FIG. 4 is a cross-sectional view similar to FIG. 3 but showing the safe unlocked and open.

FIG. 5 is a cross-sectional view of the safe taken along 5—5 of FIG. 4.

Referring to the drawings, it will be understood by those skilled in the art that the key safe may be affixed to the door or the side of the house in any suitable manner such as wood screws 6 through the back of the key safe.

The key safe has a back 7, sides 8, 9, top 10 and bottom 11 forming the main compartment of the safe which is open at the front to receive a sliding drawer having a front 12 curled over at the bottom to form a drawer pull or handle 13. The drawer has sides 14, 15, bottom 16 and back 17, its top being open to receive house key 18 when the drawer is in its extended or open position.

Attached to back 17, in any suitable manner, is an L-shaped catch 19 adapted to ride in and out with the drawer; said catch when forced inwardly, is so placed that it will trip and interlock with dog 20 on the front end of flexible spring steel arm 21 which at its rear end is firmly affixed at 22 to back 7 as by spot welding or any other suitable manner.

At the bottom rear of the key safe compartment is a housing 23 containing a coiled flat spring steel tape 24 which extends through the casing by means of orifice 25 and through the drawer back 17 by means of orifice 26, its end being attached to house key 18 in any suitable manner such as by the use of a nut 27 and bolt 28.

In key safe side 8, near the top, there is located an ordi-

2

nary master lock 29 having a keyway 30 into which may be inserted a master key 31 and which, when turned in the lock forces spring steel arm upward thereby disengaging dog 20 from its latched engagement with the top of back 17 thus allowing the drawer to be pulled outwardly until the end of L-shaped arm 19 contacts the end of key 31; thus arresting further outward movement of the drawer.

Operation

10 The key safe is attached adjacent to the lock to be opened and certain authorized persons issued master keys 31 which will enable them to operate master lock 29. The house key 18 is attached to the end of coil spring 24 by means of nuts 27 and bolt 28 and placed in the bottom 15 of the drawer and the drawer shut as shown by reference to FIG. 3.

Now any authorized person having a master key inserts it in the keyway 30 of lock 29 and on turning the key in the lock arm 21 carrying with it dog 20 is lifted so that 20 dog 20 is disengaged from locking contact with the top of back 17. The drawer is now opened by pulling outwardly on handle 13 against the increasing tension of coiled spring 24. The drawer may be pulled outwardly until L-shaped extension 19 strikes the end of key 31 25 thus arresting further outward movement of the drawer as may be seen by reference to FIG. 4. Now with the drawer pulled out the master key 31 may be removed from lock 29.

Key 18 is now removed from the drawer, and pulled 30 out against increasing tension of the coil spring 24, until it can be inserted in the lock to be opened. After unlocking the door key 18 is released by the operator; whereupon the coil spring takes over, first pulling the key 18 back into the drawer and then as the key abuts on back 35 17 the spring automatically closes the drawer to the position shown in FIG. 3, and in closing dog 20 engages the top lip of back 17 securely locking the key safe.

If the operator has failed to remove the master key 40 from the lock 29, before releasing key 18, the safe will be automatically locked on removal of the master key which will then allow dog 20 to be forced into latched contact with back 17 under the impetus of spring steel arm 21.

It will be apparent to those skilled in the art that 45 several changes may be made in the structure of my invention without departing from its scope, in which, I claim:

1. In an automatic locking key safe of the character described, a main compartment open at the front, a sliding drawer in said main compartment having a front and back, said front normally closing the opening in said main compartment, a spring mounted dog attached to the main compartment normally in locked engagement with the back of said drawer; expansible tension means attached 50 to said main compartment and having one end extending through said compartment and into said drawer and attached to a lock key normally abutting on the rear of said drawer to forcibly hold said drawer closed; means for forcing said dog out of engagement with the rear of said drawer so that said drawer and said lock key may be extended against the force of said tension means.

2. In an automatic locking key safe of the character described, a main compartment open at the front, a sliding

drawer in said main compartment having a front and back, said front normally closing the opening in said main compartment, a spring mounted dog attached to the main compartment normally in locked engagement with the back of said drawer; a coiled spring attached to said main compartment and having one end extending through said compartment and into said drawer and attached to a lock key normally abutting on the rear of said drawer to forcibly hold said drawer closed; a key operated master lock extending through said main compartment adapted to force said dog out of engagement with the rear of said drawer so that said drawer and said lock key may be extended against the force of said coiled spring.

3. In an automatic locking key safe as described in

claim 2; and an L-shaped extension arm attached to the rear of said drawer adapted to abut on said master lock key when said drawer is extended to limit further extension of said drawer.
